CLAIM

The ornamental design for a computerized tomographic scanner control keyboard, as shown and described.

DESCRIPTION

FIG. 1 is a top plan view of a computerized tomographic scanner control keyboard showing our new design;

FIGS. 2 and 3 are, respectively, left and right end elevational views thereof;

FIG. 4 is a front elevational view thereof;

FIG. 5 is a rear elevational view thereof;

FIG. 6 is a bottom plan view thereof; and

FIG. 7 is a top, front, right side perspective view thereof.

The trackball control panel is shown in broken lines in FIGS. 1-5 and 7 for illustrative purposes only and forms no part of the claimed design.
